2 SHEETS—SHEET 2.

UNITED STATES PATENT OFFICE.

GEORGE A. GEMMER, OF MARION, INDIANA.

STEERING DEVICE.

No. 829,006.

Specification of Letters Patent.

Patented Aug. 21, 1906.

Application filed December 29, 1905. Serial No. 293,785.

To all whom it may concern:

Be it known that I, GEORGE A. GEMMER, a citizen of the United States, residing at Marion, in the county of Grant and State of Indiana, have invented certain new and useful Improvements in Steering Devices, of which the following is a specification.

My invention relates to steering devices, but more particularly to steering devices for automobiles.

One of the objects of my invention is to provide a durable and highly efficient device of this character capable of withstanding the numerous strains and jolts that such a device is subject to.

In my improved construction I employ a rocker member with actuating mechanism connected to and operated by the steering-wheel, said rocker member having suitable connections to the part to be connected, say, the front wheel or wheels of an automobile, the construction and arrangement of the parts being such that movement of the steering-wheel in either direction will produce an oscillating or rocking movement of the rocker and a corresponding movement of the wheels under control.

Preferably the rocker member is formed integrally with the rock-shaft, to which a rigid arm forming a part of the connections to the wheel is secured, and the actuating means for the rocker member comprises a rotatable steering-head having reversely-threaded connections with two actuating members which bear upon the rocker at opposite sides of its center of oscillation, said actuating members being in the form of threaded sleeves. I also provide suitable means limiting the reciprocation of the sleeves and actuating members and for guiding them in their movements.

Another important element of my invention resides in such a construction and arrangement of the several parts that lost motion due to wear may be taken up by a single simple adjustment, and desirable for this purpose the actuating members, steering-head, and adjusting mechanisms and rocker-bearings are arranged in line with each other and are of annular form, whereby connection is made for carrying the usual controls of the steering-wheel.

With these and other objects in view the invention consists of certain novel features of construction, combination, and arrangement of parts, as will be more fully described, and

particularly pointed out in the appended claim.

In the accompanying drawings, Figure 1 is a sectional elevation of the steering device. 60 Fig. 2 is a cross-section below the line 2 2 of Fig. 1. Fig. 3 is an elevation of the threaded head on the steering-rod, the latter partially broken away. Fig. 4 is an elevation of one of the sleeves. Fig. 5 is a cross-section below 65 the line 5 5 of Fig. 1. Fig. 6 is an elevation of my device applied to the steering-wheel, with parts broken away and other parts in section; and Fig. 7 is a front elevation of the lower part of the steering device shown in 70 Fig. 6.

Referring to the drawings by numerals, 8 represents a rocker, slightly concave on its lower side, as shown at 9, and provided at either end with the seats 10 and 11, pivotally 75 mounted on said rocker. 12 and 13 are journals, preferably formed integral with said rocker, one of said journals being extended, as shown at 14, and adapted to receive an arm 15, rigidly secured thereto in any suitable manner—as, for example, by the nut 16 and threaded portion of the journal, as shown at 17.

18 is a casing provided with the lower members 19 and 20 of boxes in which the 85 journals 12 and 13 are seated, said casing being recessed, as shown at 21, to permit the rocker to rock therein.

22 is a tube secured to the casing in any suitable manner, as shown at 23, passing 90 through the rocker, the latter being provided with an elongated aperture 24 to permit its free movement.

25 is the usual steering-wheel, secured to the usual shaft 26 in any suitable manner, 95 said shaft being provided with the steering-head 27, secured thereto in any suitable manner, reversely threaded interiorly and exteriorly, as shown at 28 and 29.

30 and 31 represent threaded sleeves 100 engaging, respectively, with the external and internal threads of the head, said sleeves having extensions 32 and 33, which engage the rocking seats 10 and 11 and guide portions 34 and 35, which prevent rotation and compel endwise movement of the sleeves and their extensions. 36 is a casing inclosing said head and sleeves, being adapted to rest upon the casing 18 and secured thereto by any suitable means, as shown by the screws 37. 110 Said casing is provided with the upper members 38 and 39 of the journal-boxes 19 and

20, registering with said boxes on the lower casing and the sides of which are provided with ribs 40 and 41, between which the guides 34 and 35 are adapted to travel. 42 is a 5 shoulder formed on the interior of said casing to limit the movement of the guides, and consequently of the sleeves and their extensions. The neck 43 of the casing 36 is preferably constructed to fit closely the upper end of the 10 steering-head 27 and is threaded interiorly and exteriorly, as shown at 37 and 38. The inner portion of said neck is adapted to receive an annular nut 39, and the outer portion of said neck is adapted to receive a clamping- 15 ring 40, whereby the nut 39 is firmly held in position. Interposed between the head and the nut is the ring 41, resting upon the shoulder 42 of the steering-head and provided with a raceway 43 for the ball-bearings 44, and 45 20 is a groove in the lower portion of the nut 39 to form the upper raceway for the balls 44.

46 is a ball at the end of the arm 15 to form a portion of the usual ball-and-socket joint forming a part of the connections to the front 25 wheel. 47 is a casing surrounding said apparatus.

In order that the usual controls, such as the throttle and the spark-advancer, may be conveniently applied, I preferably construct 30 my device of tubing, so that there may be a continuous passage from the steering-wheel to the base, which necessitates an aperture in the sleeve 31, as shown at 48, through which passes the tube 22, this also adding to the 35 stability of the structure.

In operating my device it is first secured in any of the well-known ways to the body of the car and the arm 15 connected in the preferred form to one of the steering-knuckles 40 by any suitable rod or lever. Then by a movement of the steering-wheel, which is connected to the shaft 26, movement is imparted to

the sleeves and their respective extensions, according to the direction in which the steering-wheel is turned. As the extensions bear 45 upon the seats on the rocker a corresponding movement is imparted to the rocker, which in turn gives a swinging movement to the arm and a consequent movement to the wheels. Wear which would produce looseness of the 50 parts and consequent lost motion may be compensated for by loosening the clamping-ring and advancing the nut 39, the result being that the lost motion is taken up by a single and simple adjustment. 55

While I have herein shown and described a preferred embodiment of my invention, yet it will be obvious that the details of construction and arrangement may be modified without departing from the invention, and I 60 do not, therefore, limit myself to such details except to the extent that they are made the subject of specific claims.

I claim—

In a steering-gear, a rock-shaft provided 65 with a central aperture and pivoted seats at either end thereof, an arm rigidly secured to said rock-shaft, connections between said arm and the wheel of a vehicle, means for rocking said shaft comprising a hollow rod 70 provided with an interiorly and an exteriorly reversely threaded head, collars adapted to be threaded on said head and provided with extensions to bear upon the pivoted seats, means for turning said rod whereby a swing- 75 ing movement is given said arm and a conduit passing through said apertured rock-shaft and rod to conduct other controlling means for the vehicle directly to the operator, substantially as described.

GEORGE A. GEMMER.
